UNITED STATES PATENT OFFICE.

ROBERT G. REILLY, OF CORONA, NEW YORK, ASSIGNOR TO NORTH AMERICAN REDUCTION COMPANY, A CORPORATION OF ARIZONA TERRITORY.

METALLURGICAL FURNACE.

No. 927,283.

Specification of Letters Patent.

Patented July 6, 1909.

Application filed April 8, 1909. Serial No. 488,763.

To all whom it may concern:

Be it known that I, ROBERT G. REILLY, a citizen of the United States, residing at Corona, in the county of Queens and State of New York, have invented certain new and useful Improvements in Metallurgical Furnaces; and I do hereby declare the following to be a full, clear, and exact description of the invention, such as will enable others skilled in the art to which it appertains to make and use the same.

This invention relates to metallurgical furnaces, and has for its object the production of a furnace which will enable the metal in the ore to be converted into small shot or nodules, without the aid of fluxing material, and one which will be useful for heating ores in general or any other substances which it may be desired to treat.

With these and other objects in view the invention consists in the novel combinations of parts and details of construction more fully hereinafter disclosed and particularly pointed out in the claims.

Referring to the accompanying drawings forming a part of this specification:—Figure 1 represents an elevational view of the furnace. Fig. 2 a sectional plan view of the same taken on the line 2—2 of Fig. 3. Fig. 3 a sectional elevational view of the central portion of the furnace. Fig. 4 a sectional plan view of the auxiliary heating furnace taken on the line 4—4 of Fig. 1. Fig. 5 a detail sectional view of one of the teats 12 of the grate bars; and Fig. 6 a fragmentary detail plan view of a portion of one of the grate bars.

1 represents any suitable foundation structure for the furnace proper which may be made of stone or metal; 2 horizontal beams on which the furnace proper rests; 3 the stack or hopper into which the ore is fed; 4 an enlarged feed chamber which receives the ore and fuel; and 5 a combustion chamber which receives the ore and fuel from the feed chamber 4, as will be readily understood. The combustion chamber 5 is provided with a jacket 6, which may be adapted to contain either water or air, but in this instance I prefer to make it an air jacket. Air is conveyed to the jacket by a pipe 7, in which may be located a suitable blower not shown; the said air circulates around the combustion chamber 5 drawing heat therefrom, then leaves the said jacket through the

pipe 8 whence it passes into the connection 9, thence through the longitudinally moving pipe 10 into the hollow reciprocating grate bars 11 provided with the perforated teats 12, and finally finds its way into the combustion chamber 5. The grate bars 11 consist of the hollow rectangular pieces shown in plan view in Fig. 2, and are connected by the pipes or rods 13 with an eccentric rod 14 driven by an eccentric 15 mounted on the power shaft 16. The rod or pipe 13 passes through a suitable stuffing box 17 and the pipe 10 reciprocates through a pair of stuffing boxes 18 and 19 as shown. There may be any number of these grate bars 11 and eccentrics 15, and in the drawings I have shown four.

Beneath the grate bars are horizontal supporting bars 20, which rest at their ends upon two longitudinal bars 21, shown in plan view in Fig. 2, and one of which is shown in elevation in Fig. 3. The ends of these longitudinal bars 21 rest upon short vertical rods 22 supported by the short ends 23 of levers 24 pivoted at 25 to a lug 26 suitably supported from the main frame.

27 represents weights which may be adjusted along the levers 26 and thereby raise the rods 22, the longitudinal bars 21 and with them the supporting bars 20 and grate bars 11 to any desired extent. In other words, the construction just described takes the strain of the ore resting on the grate bars off of the reciprocating tubes 13 and 10 and the stuffing boxes through which they pass, and thereby permits the eccentrics 15 to more freely reciprocate the grate bars 11 at the bottom of the combustion chamber 5.

30 represents a suitable hopper which converges to a discharge opening 31 controlled by a reciprocating plunger 32 connected to the link 33 supported by the pivoted link 34 and joined to the reciprocating rod 35 connected to the crank or disk 36 on the power shaft 37. The discharge opening 31 delivers into the discharge passage 38 which may empty into suitable cars or other receptacles, or it may pass the ore into the auxiliary heating furnace 39 as desired.

Leading from the connection 9 is a pipe 40 provided with a valve 41 leading into the hopper 30, as best shown in Fig. 3, and by suitably manipulating the valve 41 the air may be directed into said hopper below the grate bars when desired. The walls of the

jacket 6 are suitably connected by bolts 42, and 43 represents a suitable baffle plate against which strikes the cold air entering the jacket through the pipe 7, and which being spaced from the hot wall of the combustion chamber 5, prevents the same from being impaired by a too sudden impact of cold air.

There may be several pipes 8 joining the jacket 6 and the connection 9, and in Fig. 2 there are shown two. Also there may be a pipe 44 joining these pipes 8 as shown in Figs. 1 and 3. The tops of the supporting bars 20 are preferably rounded, in order that the grate bars may slide the more easily thereover and the said grate bars are provided with holes 45 through which the ore may drop into the hopper 30 as best shown in Figs. 2 and 3. They are also spaced somewhat apart in order that the ore may drop 20 between them.

So far as now explained, it will be clear that the teats 12 of the reciprocating grate bars will serve to thoroughly stir the ore and at the same time, to deliver air into intimate contact substantially with all the particles thereof. In other words, the ore in the combustion chamber 5 will be thoroughly and constantly stirred while air is evenly and constantly distributed throughout its mass. There is no flux put into this ore and the temperature in the combustion chamber 5 is kept below the melting point of the ore, but above the melting point of the metal carried by the ore, the result is that the oxygen delivered to the ore will ignite the fuel in the chamber, and it will also serve to carry off more or less of the ignitable constituents of the ore, thereby leaving the metal in the individual lumps in the state of shot or small nodules. If at the same time it is desired to furnish air underneath the grate to increase the combustion, the valve 41 may be manipulated and the temperature thereupon raised.

In some ores there may be individual particles that are not thoroughly shotted, and it is desirable to carry these lumps or particles through a second treatment, and even in some ores, in order to complete the process, it is sometimes desirable to carry them through such second treatment. In either case the discharge passage 38 may be caused to deliver into an auxiliary heating furnace 39, any ore that needs further treatment. This auxiliary furnace is provided with a central receptacle 50 which receives the ore, and the walls 51 of which are provided with the perforation 52 through which air in the air chamber 53 enters the receptacle 50. The air is received into the air chamber 53 through the passage 54 which may be suitably connected with a blower or other source of air pressure.

The air entering the receptacle 50 is carried upwardly through the pipe 55 and into the stack 3 of the main furnace or of course it may be delivered in any other suitable

manner. The ore from the receptacle 50 is discharged into a passage 60 by means of a plunger 61 operated by the connections 62 and 63 joined to the crank or disk 64 mounted on the power shaft 65 and such connections are preferably supported by a swinging link 66 as shown. The ore after having been delivered into the passage 60 may then be discharged into suitable cars or other receptacles, or if desired, it could be, of course, carried through a third treatment.

67 represents a horizontal support of the auxiliary furnace and 68, a vertical support therefor.

The operation of the furnace will be clear from the foregoing, but may be briefly summarized as follows:—Ore and sufficient fuel such as coal to maintain the necessary temperature, are fed into the combustion chamber 5, wherein the ore is continuously stirred by the reciprocating grate bars and teats while air is being delivered through said teats into intimate contact with said ore and throughout its mass. The ore while being thus treated is allowed to drop through the openings 45 in said bars and through the spaces between the same into the hopper 30, whence it is delivered by the plunger 32 and passage 38 into suitable receptacles, or into the secondary furnace 39 for further treatment.

The temperature in the combustion chamber is so regulated that it is not permitted to rise high enough to melt the ore, but yet is maintained sufficiently high to melt or to shot or nodulate the metal carried by the ore. After the ore is thus nodulated, it may be passed through suitable crushing machinery and the metal recovered in any suitable manner.

It is evident that the arrangement of parts and details of construction may be varied by those skilled in the art without departing from the spirit of this invention; therefore, I do not wish to be limited to the features disclosed except as is required by the claims.

What I claim is:—

1. In a metallurgical furnace, the combination of a feed chamber for the ore; a combustion chamber; a movable grate mechanism at the bottom of said combustion chamber, adapted to support the ore; and means to reciprocate said grate mechanism while the furnace is in operation, substantially as described.

2. In a metallurgical furnace, the combination of a feed chamber for the ore; a combustion chamber; a movable grate mechanism at the bottom of said combustion chamber provided with perforated teats, adapted to support the ore; means for supplying air to said teats; and means to reciprocate said grate mechanism while the furnace is in operation, substantially as described.

3. In a metallurgical furnace, the combi-

nation of a feed chamber; a combustion chamber; a hollow reciprocating grate bar provided with perforated teats, adapted to support the ore; and means to supply air to said teats, substantially as described.

4. In a metallurgical furnace, the combination of a feed chamber; a combustion chamber; a hollow reciprocating grate bar provided with perforated teats, adapted to support the ore; means to reciprocate said grate bar; a jacket in which air may be heated; and means connected with said jacket to supply air to said teats, substantially as described.

15 5. In a metallurgical furnace, the combination of a stack; a feed chamber; a combustion chamber; an air jacket surrounding said combustion chamber; a plurality of hollow grate bars at the bottom of said combustion chamber provided with perforated teats; connections between said air jacket and said hollow grate bars adapted to supply air to said teats; a hopper; and a discharge passage for the ore beneath said hopper, substantially as described.

20 6. In a metallurgical furnace, the combination of a stack; a feed chamber; a combustion chamber; an air jacket surrounding said combustion chamber; a plurality of hollow grate bars at the bottom of said combustion chamber provided with perforated teats; connections between said air jacket and said hollow grate bars adapted to supply air to said teats; a hopper; connections 25 by which air from said jacket may be fed to said combustion chamber through said hopper; and a discharge passage for the ore beneath said hopper, substantially as described.

7. In a metallurgical furnace, the combination of movable grate bars adapted to receive ore thereon and provided with bearings; and means by which the weight of said bars and ore may be taken off the said bearings while the said bars are being moved, substantially as described.

8. In a metallurgical furnace, the combination of reciprocating hollow grate bars provided with bearings; means to reciprocate said bars; adjustable means to relieve the pressure of said bars on said bearings while the furnace is in operation; and means to supply air to the interior of said hollow bars, substantially as described.

9. In a metallurgical furnace, the combination of reciprocating hollow grate bars 55 provided with perforated teats and with bearings; means to reciprocate said bars; adjustable means comprising a weighted lever to relieve the pressure of said bars on said bearing while the furnace is in operation; an air jacket; and means connected to said jacket adapted to supply air to the interior of said hollow bars, substantially as described.

10. In a metallurgical furnace, the combination of a stack; a feed chamber; a combustion chamber; an air jacket surrounding the combustion chamber; a plurality of hollow grate bars provided with holes 45 through which ore may pass, and with perforated teats; connections between said bars and jackets; a plurality of supporting bars for said grate bars; a plurality of levers provided with adjusted weights adapted to raise said grate bars; a hopper beneath said grate bars; 75 and a discharge chute below said hopper, substantially as described.

11. In a metallurgical furnace, the combination of hollow, movable, grate bars provided with perforations adapted to supply 80 air in intimate contact with the ore while said bars are moving; means to move said bars while the furnace is in operation; means to supply air to said bars; a discharge passage and a second heating furnace, into 85 which said passage delivers, substantially as described.

12. In a metallurgical furnace, the combination of hollow, movable, grate bars provided with teats having perforations adapted 90 to supply air in intimate contact with the ore while said bars are moving; means to move said bars while the furnace is in operation; means to supply air to said bars; a hopper; a discharge passage; a reciprocating plunger in said passage; a second heating furnace provided with an air chamber; and a heating chamber in said furnace into which 95 said passage delivers, substantially as described.

In testimony whereof, I affix my signature, in presence of two witnesses.
